UNITED STATES PATENT OFFICE.

ALBERT HENRY MIDGLEY, OF ACTON VALE, ENGLAND, ASSIGNOR OF ONE-HALF TO
C. A. VANDERVELL & COMPANY LIMITED, OF ACTON VALE, ENGLAND.

SELF-REGULATING CONTINUOUS-CURRENT DYNAMO.

1,419,071.

Specification of Letters Patent. Patented June 6, 1922.

Application filed December 21, 1918. Serial No. 267,821.

To all whom it may concern:

Be it known that I, ALBERT HENRY MIDGLEY, a subject of the King of Great Britain and Ireland, and residing at Warple Way,

5 Acton Vale, in the county of Middlesex, England, have invented certain new and useful Improvements in and Relating to Self-Regulating Continuous-Current Dynamos, of which the following is a specification.

10 This invention relates to an improved variable speed self-regulating continuous current dynamo.

The main object of the invention is to provide a method of self-regulation which shall 15 be especially useful in connection with variable speed dynamos of small dimensions.

It has previously been proposed in connection with variable speed self-regulating continuous current dynamos to short-circuit 20 a plurality of armature conductors by means of a single wide brush, or two brushes, connected together directly, or through the intermediary of an adjustable resistance, which short-circuited conductors were arranged 25 in the armature cross-field acting in conjunction with auxiliary poles. The object of this arrangement was to provide a demagnetizing flux acting in opposition to the main flux of the machine so as to produce 30 a constant current independent of the variation in speed of the dynamo.

According to the present invention the demagnetizing field acting in opposition to the main field for producing a constant current 35 independent of the speed variations of the dynamo, is produced by a short-circuited current flowing through the armature conductors lying in the fringe of the main poles, viz, under the lagging pole tips with respect 40 to the direction of rotation of the machine, that is to say, it is not produced by a cross-flux but by the main flux itself, so that the auxiliary poles are entirely dispensed with.

Figures 1, 2 and 3 in the accompanying drawings illustrate diagrammatically and, 45 by way of example, three different modes of carrying the invention into effect.

Referring to the arrangement illustrated in Figure 1, the two wide brushes, or the two pairs of brushes $a\ a$ and $a'\ a'$, connected together by a short-circuiting conductor $b\ b$, are arranged to short-circuit the armature conductors $c\ c'$, respectively, which lie in the fringe of the poles N S where the density of the magnetic flux is a maximum, the current flowing through these short-circuited armature conductors producing a demagnetizing field A acting in opposition to the main field. Each of the pairs of brushes $a\ a$ and $a'\ a'$ may be replaced by a single wide brush. 60

According to the arrangements illustrated in Figures 2 and 3, the main brushes B B' of the machine are arranged in a neutral position, and in addition thereto use is made either of two auxiliary wide brushes $a\ a$, 65 (Fig. 2), or of two pairs of short-circuited brushes $a'\ a'$, (Fig. 3), arranged underneath the backward edge $N^1 S^1$ of the poles N S.

It will thus be seen that in the arrangement according to the present invention, the wide 70 brushes, or their equivalent, are shifted back, as compared with the usual shifting forward of the brushes for ensuring sparkless commutation.

The invention is applicable, not only to bipolar, but also to multi-polar machines. 75

What I claim is:—

A variable speed self-regulating continuous current dynamo having an armature and armature conductors thereon, main poles, 80 and means for short-circuiting a plurality of armature conductors lying under the lagging pole tips, as set forth.

In testimony whereof I have signed my name to this specification.

ALBERT HENRY MIDGLEY.
